UNDERGARMENT

Leonard G. Arpin and Helen G. Arpin, Montclair, N. J.

Application March 19, 1945, Serial No. 583,632

3 Claims. (Cl. 2—224)

1

This invention relates to undergarments of the type commonly known as "shorts."

One of the objects of this invention is to provide an unusual degree of comfort in the wearing of these garments, this advantage being obtainable in hot as well as cold environments.

Another object of this invention is to combine the above mentioned feature with extreme simplicity of construction and conservation of material.

Another object of this invention is to provide a simple means of automatically converting the area of fabric at the crotch, from a series of bunched and uncomfortable folds to a well-formed front crotch portion possessing an unusual degree of comfort and conformity to the anatomical requirements of the wearer.

Other objects of this invention will become apparent from the following description it being understood that the above general statements of the objects of this invention are intended to describe and not to limit it in any manner.

Referring to the drawing:

Figure 1 is a plan view of a strip of cloth material before being folded and connected to form the finished garment.

Figure 2 is a front elevational view of the finished garment.

Figure 3 is a perspective view of the garment as worn.

The strip of cloth material 10 is folded and sewn at its ends to produce the usual hems 11 and 12. A fly 13 is provided, although it may be omitted if desired. Elastic tapes 14 and 15 are sewn to one end of the cloth strip and, when sewn to the other end, form the waist engaging portion of the garment as illustrated in Figure 2.

The important feature of this invention is the provision and disposition of pleated tucks or shirring 16 formed at the side edges of the garment as seen in Figure 1.

Referring to Figure 2, the folded strip is seen to provide a back member B and a front member F. The series of pleated tucks are located substantially on the lower half of the front member but preferably, although not necessarily, do not extend to the bottom edge of said front member F.

Whereas the strip of fabric 10 is initially a planar member with straight edges, the provision of the pleated tucks causes the treated side edges to curve inwardly, reducing the width of the garment at that area. However, since the material between the pleated side edges remains unpleated, so that the side edges are shortened in relation to the length of the central portion of said area,

this area is necessarily formed with a fullness which provides the advantages hereinafter set forth.

The area defined by the pleated side edges will be referred to herein as the crotch portion, its shape being arranged to conform to the anatomical requirements of a male wearer although a female may use the garment as well.

The simple provision of the pleated side edges 10 results in many unexpected advantages. For example, this treatment of the side edges causes them to curve inwardly thereby conforming to the curvature of the torso adjacent to the top inner edge of the thigh. This curvature is desirable only until the extreme bottom of the crotch is reached whereupon the pleating ceases and the garment is permitted to fan out as it approaches the posterior of the wearer.

In addition, the unpleated area between the 20 side edges achieves a fullness at the crotch portion which is contributed to by two effects. First, since the area is unpleated between the shortened side edges, the excess of material contributes to this fullness. This may be called a longitudinal 25 contribution since the material comes from the greater length of the unpleated in relation to the pleated areas. Second, the inward curvature of the side edges contribute thereto in what may be called a lateral manner. Finally, the combination 30 of these contributions produce a result of forming an excellent pouch of concavo-convex cross section as illustrated in Figure 3. The curved side edges are automatically drawn up in use so that the genitals are shielded from the thighs of the wearer and thus from the perspiration annoyances caused by disregard of this requirement. It has been found that the pleated side edges tend to assume this position without manifesting a tendency to bunch between the 35 genitals and the thighs. This tendency of the side edges to draw up into a comfortable position is attributable to the reduced width and form fitting nature of the crotch portion automatically achieved by the pleating operation.

40 The conformity of the garment to the fundamental requirements of such articles is achieved with a minimum of labor as well as material and the effectiveness of the garment while avoiding excessive material makes it highly desirable in 45 tropical or similar climates.

50 While it is obvious that the dimensions of the garment may vary somewhat according to the size of the wearer, we have found that a width of material about 11 inches and a folded length of 55 about 15 inches (referring to the garment as

shown in Figure 2), provides a garment useable over a wide range of conventional wearing sizes.

We have shown a preferred embodiment of our invention, but it is obvious that numerous changes and omissions may be made without departing from its spirit.

What is claimed is:

1. An undergarment comprising a unitary strip of fabric folded upon itself to form front and back members, the ends of said folded strip being interconnected to form waist engaging means, and a crotch portion formed on said front member, said crotch portion being defined by an area of said front member having pleated side edges whereby said pleated side edges are curved inwardly in relation to the unpleated edges of said front member so as to conform to the bottom torso curvature of a wearer, said pleated side edges forming said crotch portion of less width and greater fullness than the remainder of the undergarment.
2. An undergarment comprising a strip of material folded upon itself to form front and back members, elastic strips interconnecting said members to form a waist engaging portion, a crotch portion integral with said front member, said crotch portion being defined by an area of said front member having pleated tucks formed on the side edges thereof to shorten the normal length of the material at said side edges and to

cause said side edges to curve inwardly in relation to the unpleated edges of said front member reducing the width of said front member at said area and causing the central portion of said area to assume a fullness relative to said pleated side edges, said inward curvature causing said crotch portion to conform to the bottom torso curvature of a wearer.

3. An undergarment comprising a strip of material folded upon itself to form front and back members, elastic strips interconnecting the ends of said members to form a waist engaging portion, a crotch portion integral with said front member, said crotch portion being defined by an area of said front member having pleated tucks formed on the side edges thereof to shorten the normal length of the material at said side edges and to cause said side edges to curve inwardly from their normal position reducing the width of said front member at said area, said area being located substantially on the lower half of said front member without reaching the bottom edge thereof, the said pleated side edges of said area causing the central portion of said area to assume a fullness relative to said pleated side edges, the inward curvature of said side edges causing said crotch portion to conform to the bottom torso curvature of a wearer.
